CLAIM

The ornamental design for a terminal, as shown and described.

DESCRIPTION

FIG. 1 is a perspective view of a terminal;
 FIG. 2 is a front view of the design of FIG. 1;
 FIG. 3 is a rear view of the design of FIG. 1;
 FIG. 4 is a right side view of the design of FIG. 1;
 FIG. 5 is a left side view of the design of FIG. 1;
 FIG. 6 is a top view of the design of FIG. 1; and,
 FIG. 7 is a bottom view of the design of FIG. 1.

(Continued)

The broken lines in the drawings depict portions of the terminal that form no part of the claim.

1 Claim, 7 Drawing Sheets
